Francis O'Hardey

ATTORNEY.

UNITED STATES PATENT OFFICE

CHARLES F. DOWRIE, OF DETROIT, MICHIGAN, ASSIGNOR, BY MESNE ASSIGNMENTS, TO THE TIMKEN SILENT AUTOMATIC COMPANY, OF DETROIT, MICHIGAN, A CORPORATION OF MICHIGAN

VENT CAP

Application filed April 27, 1931. Serial No. 533,183.

The present invention relates to vent caps for otherwise closed tanks designed to contain inflammable or other liquids. Among the objects of the invention is to cheapen the construction of such caps and at the same time provide certain other characteristics of advantage over the known forms of caps.

Another object is a vent cap that admits of more universal application than the known forms. Other objects will readily occur to those skilled in the art upon reference to the following description and the accompanying drawing, in which Fig. 1 is sectional view on line 1—1 of Fig. 2 showing the cap construction, and Fig. 2 is a plan view from below.

As indicated in the drawing the cap comprises four elements, first the cover 10 which consists of a drum-shaped metal member the sides of which 11 are substantially parallel with the vertical axis. If it is desired to make the cap easy to disassemble the sides 11 may be slightly flared as shown on the drawing.

Adapted to fit into the lower edge of the cap 10 is a spider element 12 which has a circular opening 13 eccentrically located with respect to the cap and having the remaining portions cut away to leave several spokes, each provided with a small ear 14, there being also ears 14 at other locations in the several openings.

The third element consists of the clamp member 16 which is of the well known split ring or clamping ring construction, but which is provided at one end with several ears 17 which are bent inwardly and then upwardly over the inner edge of opening 13.

The fourth element of the cap is a screen 20 which overlies the spider member 12 and is perforated to receive the ears 14 and also provided with an opening of substantially the same area as opening 13.

The screen member is first assembled on the spider by bending over the several ears 14, these having been passed through the perforations of the screen and then the clamp member 16 is put in position with the ears 17 holding it in place over the opening 13. When these parts have been assembled the

spider carrying the screen is pressed in the lower end of the cap member 10 where it is held securely.

Now having described the invention and the preferred form of embodiment, it is to be understood that the said invention is to be limited not to the specific construction described and illustrated, but only by the scope of the claim which follows.

I claim:

A vent cap comprising a dome portion, a spider fixed in the lower edge thereof and having a circular opening eccentrically located therein, integral tongues extending from the edges of the arms of said spider, a screen fixed to the inner face of said spider by means of said tongues, and an expanding clamp mounted over the said circular opening and substantially concentric therewith, said clamp having tongues bent to embrace the edge of said opening.

In testimony whereof, I sign this specification.

CHARLES F. DOWRIE.
